US00D876616S

(12) **United States Design Patent** (10) Patent No.: **US D876,616 S**
(45) Date of Patent: **** Feb. 25, 2020**

(54) **HEADGEAR**

(71) Applicant: **Fisher & Paykel Healthcare Limited**,
Auckland (NZ)

(72) Inventors: **Craig Robert Prentice**, Auckland (NZ);
Bernard Tsz Lun Ip, Auckland (NZ);
Mark Arvind McLaren, Auckland (NZ);
Kyle Gregory Brown, Auckland (NZ);
Chris Onin Limpin Hipolito,
Auckland (NZ); **Mark Richard Tomlinson**,
Auckland (NZ); **Melissa Catherine Bornholdt**,
Auckland (NZ)

(73) Assignee: **Fisher & Paykel Healthcare Limited**,
Auckland (NZ)

(**) Term: **15 Years**

(21) Appl. No.: **29/670,353**

(22) Filed: **Nov. 15, 2018**

Related U.S. Application Data

(60) Continuation of application No. 29/595,871, filed on Mar. 2, 2017, now Pat. No. Des. 837,971, which is a division of application No. 29/540,683, filed on Sep. 25, 2015, now Pat. No. Des. 784,515.

CLAIM

The ornamental design for a headgear, as shown and described.

DESCRIPTION

FIG. 1 is a top, front and left side perspective view of a headgear showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

Broken lines are used to illustrate portions of the headgear that form no part of the claimed design.

1 Claim, 7 Drawing Sheets
